UNITED STATES PATENT OFFICE.

ERNEST STARBUCK, OF PEORIA, ILLINOIS, ASSIGNOR, BY DIRECT AND MESNE ASSIGNMENTS, TO EDWARD M. SMITH, OF PEORIA, ILLINOIS.

RUBBING-POST.

1,212,415.

Specification of Letters Patent. Patented Jan. 16, 1917.

Application filed December 14, 1912. Serial No. 736,783.

To all whom it may concern:

Be it known that I, ERNEST STARBUCK, a citizen of the United States, residing at Peoria, in the county of Peoria and State of Illinois, have invented certain new and useful Improvements in Rubbing-Posts; and I do hereby declare that the following is a full, clear, and exact description of the invention, which will enable others skilled in the art to which it appertains to make and use the same.

This invention relates to a hog greaser or rubbing post. It pertains particularly to a rubbing post having an elevated receptacle for oil or a disinfectant and one or more smaller auxiliary receptacles to receive and measure small quantities of the oil from said smaller receptacles upon the "rubbing" part or parts.

In certain types of hog greasers there is a movable "rubbing" part operated by the hog, the movement of which results in liberating the oil or disinfectant which runs down said part. As very often occurs the animal will sometimes lie against the member and thereby hold the oil exit open with the result that the oil is wasted and the rubbing post is of little use until the oil is replenished, and due to this loss the cost of the oil in time becomes considerable. In view of this, it is my purpose to provide a hog greaser in which but a small portion of the oil will be discharged each time the animal uses the post the oil being prevented, automatically, from flowing when this small portion has been discharged and when the hog lies against the rubbing part.

Therefore, an object of the invention is to provide a receptacle for holding a very small quantity of oil which receptacle has communication with and is automatically supplied from a larger receptacle, the oil in the said smaller reservoir being discharged in the rubbing movement of the animal upon the rubbing part.

Another object of the invention is to provide, in a rubbing post, an elevated tank or receptacle for oil which has a smaller receptacle in communication therewith that can be alternately filled and discharged upon the rubbing surface due to the movements of the animal.

Another object is to provide a main receptacle for oil and a smaller one in connection with and to be supplied from it, and a dou-

ble valve adapted in one of its extremes of movement to permit entrance of oil to the smaller receptacle and in its other extremity to allow the discharge therefrom.

Another object is to furnish a rubbing member for a device of the nature described to operate a part for the discharge of an oil or disinfectant, said member being so mounted that the smallest as well as the largest animal may readily operate it.

Another object is to construct a rubbing post of simple form and of low cost.

The invention, besides the above, relates also to certain details of construction as will be pointed out herein assisted by the accompanying drawing in which:

Figure 1 is an elevation of my rubbing post, parts of which are shown in section. Fig. 2 is a plan of a portion of the same. Fig. 3 is an enlarged section of parts shown in Fig. 1. Fig. 4 shows a part of a valve stem in perspective. Fig. 5 shows a portion of a leg of the rubbing post in perspective. Fig. 6 shows the under side of the upper portion of the device, parts of which are shown in section, and Fig. 7 shows a "rubbing" member in perspective.

A is a receptacle for the oil, preferably a casting, provided with any suitable lid B. Extending from the bottom of the receptacle 75 is a hollow centrally disposed extension C into which is screwed, driven, or otherwise secured, a standard consisting for instance of a piece of piping D.

E indicates a base preferably having three legs F and having also a socket G into which the lower end of said pipe D is screwed, driven, or otherwise secured.

Cast with the bottom of the receptacle A are spaced hollow extensions H, I having shown three in the present instance. The extensions are tubular and each constitutes a receptacle for oil, being provided with an upper and lower wall. The upper one has an opening J and the lower one an opening K which, in the present instance, is much larger in diameter than the said opening J. A valve stem L extends vertically through each receptacle and through both the openings. The stem slidably fits the upper opening and it is furnished near its lower end with a series of wings M which slidably fit the opening K, there being spaces N left between the wings for the passage of the oil as will be more fully described later.

The stem L carries at each end a leather valve washer O adapted to rest upon and close the openings J K. Outside of each of these is a suitable washer P followed by nuts 5 or heads Q to hold the same in place. The upper end of the stem has a series of notches R, Fig. 4, which permit the oil contained in the receptacle A to flow into the receptacle H when the valve is raised and 10 occupies the position shown in Fig. 1. An expanding spring S carried by the stem bears at one end against the upper wall of the receptacle H and its lower end rests and bears upon the wings M. The distance 15 between the two valve leathers O is somewhat greater than the outside measurement of the said receptacle H so that the stem can have a slight vertical motion, the spring S constantly tending to hold the upper valve O upon its seat at the top of the said receptacle H.

It is clear that when the stem is in its highest position the oil will enter the receptacle H as already described but cannot run 20 out of the latter by reason of the fact that the lower valve O is then seated against the bottom opening K and the means for holding the valve in this position will be described presently. But when the spring is permitted to act the opening K is exposed 25 by lowering the stem L, the lower valve O permitting the oil to run out through the openings N. It will be observed that in broken lines in Fig. 3 the extremities of the stem L are reduced in size so as to be smaller 30 in diameter than the body of the stem. In this way the valves O can rest upon the resulting shoulders and can positively close the openings J K.

40 T is a rubbing member arranged in an upright position between the base E and receptacle A and swings on a vertical axis. To this end a cast hollow boss U depends from the bottom of the receptacle A at three 45 places as indicated in Fig. 2 and in the base E is a socket V in line with each, but one of which is shown, see Fig. 1. The upper end of the said member T is provided with a trunnion W adapted to seat in the socket of the said boss U while the lower end of the member has an adjustable trunnion 2. This 50 has a vertical slot 3. Bolts 4 extend through the slot and a part of the member, Fig. 1. This structure permits the said trunnion 2 to be adjusted vertically as desired so that 55 the member T can be given as free movement as desired. The trunnions W at the upper ends of the members T are stationed at one side of the housings H, as shown in 60 dotted lines in Fig. 2. The said members T are broad in horizontal measurement and the trunnions W, 2, are mounted at one edge of the same so that the members will be made to swing when pressure is placed upon 65 them. Extending from the upper end of

each said member T, at about the middle, is a finger 5 which has an inclined upper surface adapted to have contact with the lower end of the stem L. A spring 6 is mounted on the upper trunnion W one end bearing 70 upon the member L the other against some fixed part of the apparatus, for instance the part C extending from the bottom of the receptacle A. The tendency of the spring is to hold the member T outward with its finger 5 in contact with the lower end of the valve stem L, the incline of the finger 5 being such that when the member is moved outward the lower end of the stem will be positively engaged and the lower valve O 80 will be firmly held upon its seat and prevent the discharge of oil from the receptacle H.

The hog in rubbing upon the member T swings it on its axis and in consequence the finger 5 is shifted allowing the spring S to force the stem L downward and cause the upper valve O to seat. There is then no communication of the receptacle H with the receptacle A. This movement permits the oil to pass out of the receptacle H through the opening K and it then flows down the finger 5 and upon the outer surface of the member T from which the hog receives it in his rubbing movements. The spring 6 exerts considerable force so that it will overcome and compress the spring S and overcomes what friction there may be.

It is observed that if the member remains in such a position as to allow the valve to 100 retain its lowest position there can be no loss of oil since none can be discharged from the receptacle A until the valve is again raised at the time the member T is allowed to regain its normal position at which time its 105 inclined surface will raise said valve. In assembling the rubbing post the sockets that receive the trunnions are brought in line vertically so that the members T can be easily put in place and in putting these in 110 position the upper trunnions are properly seated and the lower adjustable ones can then be properly adjusted in their sockets in the base E. It is thus seen that although 115 the parts of the body of the device may be permanently connected the members T can be removed and replaced with ease.

It is to be stated that any manner of mounting the member T may be resorted to since it is not the desire to be confined to 120 what has been described as the mounting means. The advantage, however, in pivoting the member at both ends and offsetting the pivots substantially as shown, is that no more power is required at one point in its 125 length than at another in order to swing it so that an animal, no matter how small, may as easily move it as a very large animal. The members, of course, may be roughened on their outer faces if desired and it is ob- 130

served that I suspend the said members above the legs F so that any excess oil can fall thereon, the latter serving as receptacles which, in extending for some distance 5 away from the members, and being comparatively low, can be used by the animal upon which to rub his under parts. The receptacle is constituted by providing ribs 7 which are raised above the edges of the legs 10 which are raised above the edges of the legs 7 as clearly shown. The surface of the leg is also roughened in any desired way for instance by providing a series of raised ribs 8 for the animal to rub upon and from which the oil will be taken, the ribs distributing 15 the oil upon the affected parts of the animal in the rubbing action.

I wish to state that I am aware of a device 20 that measures a disinfectant between two valves for spraying animals but the structure employed is complicated and involves considerable expense in its manufacture besides which the spraying nozzle is suspended above the place occupied by the animal in rubbing and in being thus suspended will 25 be either too high or too low according to whether a small animal or a large one uses the device. In one case the fluid will be wasted in large quantities each time a small animal is treated because the nozzle is too 30 far away, and in the other event the animal cannot get into position, because the nozzle hangs too low, and cannot receive the benefit of the fluid. It is highly important to arrange for a saving of as much of the fluid 35 as possible in a rubbing post because of the cost. The method of providing for such saving is to measure a small quantity of the fluid each time the device is used and to effect a still further saving the fluid must 40 be discharged directly upon a surface for the animal to rub against. To this end I have arranged the structure herein described which while measuring the fluid at an elevation high enough to permit an animal of 45 any size to approach, also arranges for the delivery of the required small amount upon a member easily rubbed against and operated by the largest and smallest animals alike.

50 My rubbing post or hog oiler is distinguished from others of its class from the fact that the rubbing member T is normally in engagement with the valve stem to hold the valves O constantly raised so that the 55 small receptacle is kept filled with the fluid and ready to deliver a measured quantity upon pressure being applied to the said rubbing member to withdraw it from and release the valve. At this time the valve seats 60 to prevent oil being supplied from the large receptacle to the now open small one. The member T directly underhangs the valve so as to catch all of the oil upon its surface.

The general form of my rubbing post or 65 oiler is such that it can be set in any con-

venient or desired location where the animals may reach it from all sides.

I may make such slight changes in my device as might suggest themselves without departing from the spirit of the invention 70 and the scope of the claims.

Having described my invention, I claim:—

1. In a rubbing post, the combination of a support, an upright rubbing bar hingedly mounted on the support and adapted to 75 swing, and mechanism arranged to measure a given quantity of fluid disposed above and directly engaged by a portion of the rubbing bar, the latter underhanging the place of discharge from said mechanism and 80 adapted by pressure of the animal upon it to permit the operation of the mechanism for liberating and discharging such measured quantity of fluid directly upon that 85 side of the rubbing bar against which the animal rubs.

2. In a rubbing post, the combination of a support, an upright rubbing bar mounted on a vertical axis on said support, and in position to be engaged by an animal, and 90 mechanism arranged to measure a given quantity of fluid disposed above and directly engaged by a portion of the rubbing bar, the latter underhanging the place of discharge from said mechanism and adapted 95 by pressure of the animal upon it to permit the operation of the mechanism for liberating and discharging such measured quantity of fluid directly upon that side of the rubbing bar against which the animal rubs. 100

3. In a rubbing post, the combination with a receptacle for holding a fluid, a second smaller receptacle including an opening communicating with the first said receptacle, said second receptacle also having 105 a discharge opening, a stem including spaced valves each adapted to cover one of the openings, said valves in their movement adapted to alternately close one and open the other of said openings, and a rubbing 110 member having a part to engage and move the stem in the direction of one of the openings, means to hold it elastically in engagement with said stem and hold one of the valves on its seat, and means constantly 115 tending to move the valves in opposition to the said rubbing member.

4. In a hog oiler, the combination of a pair of elevated receptacles for holding fluid there being an aperture connecting the two, 120 there also being an outer exit-aperture for one of said receptacles, a valve adapted for closing the first said aperture, a second valve adapted for closing the said exit-aperture, 125 said valves operating in unison to alternately close one and expose the other of the apertures, a rubbing member adapted to be operated by an animal rubbing upon it including a part to operate the valves, the same adapted to hold one of the valves seat- 130

ed and the other unseated, said rubbing member underhanging the exit-aperture to receive the fluid upon it, and means to operate the valves in opposition to the movement imparted by said rubbing member.

5. In a hog oiler, the combination of a pair of receptacles including a communicating opening between them, and including also an outer discharge opening from one 10 of said receptacles, a pair of valves including a stem, one of said valves adapted to overlie and close the outer discharge opening, the other adapted to close the other opening, the latter being normally exposed, 15 a rubbing member including means to hold it elastically in engagement with the stem, and means tending to operate the valves in opposition to the said rubbing member.

6. In a hog oiler, the combination of a 20 pair of receptacles including a communicating opening between them, and a discharge opening, a pair of valves including a part to carry them extending outside the receptacle, each valve adapted for closing 25 one of the openings, the said openings being spaced from one another whereby when one of the valves is closed the other is open, a rubbing member normally in engagement with a part of the valve lying outside the 30 receptacle and adapted when moved by an animal to release the valves, and means to move the valves and change their seating relation when released.

7. In a hog oiler, the combination of a 35 submerged receptacle having an opening in two of its walls, a valve structure comprising two spaced portions each adapted to close one of the openings, said portions arranged to close one of the openings when 40 the other is opened, means to seat one of the portions elastically upon its opening, a rubbing member adapted to operate the valve against and in opposition to said means, and normally holding the valve in one of its 45 extreme positions, the latter being released by pressure of an animal upon said rubbing member.

8. In a hog oiler, the combination of a 50 submerged receptacle having an opening in two of its walls, a valve structure comprising two spaced portions each adapted to seat upon one of the openings and spaced with 55 respect to one another and the openings whereby when one is seated the other remains unseated, means to hold one of the portions of the valve elastically upon its respective opening, a rubbing member including means to hold it elastically in engagement with the valve and to place pressure upon said valve in opposition to the 60 first said means, said rubbing member being arranged when pressure is placed upon it to release the valve.

9. In a rubbing post the combination with 65 an elevated receptacle for fluid, a second

relatively smaller receptacle having an opening in two of its walls, one of them communicating with the first said receptacle, a double valve for said second receptacle comprising two portions adapted to simultaneously close one of said openings and open the other and including a part extending outside said second receptacle, the valve- 70 portions being spaced apart and fixed relatively, and a rubbing member below the receptacle upon a vertical axis and having a part to engage the extended part of the valve and adapted by each pressure of an animal thereon to release the valve structure to permit the closing of one valve and the 80 opening of the other to release a single quantity of fluid upon said member.

10. In a rubbing post the combination with an elevated receptacle for fluid, a second relatively smaller receptacle having 85 an opening in each of two of its walls, one of them communicating with the first said receptacle, a double valve for said second receptacle comprising two spaced portions adapted to simultaneously close one of said 90 openings and open the other and including a part extending outside said second receptacle, the valve-portions being fixed relatively, a member lower than the receptacle in position to receive fluid upon it and 95 mounted to swing on a vertical axis and having a free extension to engage the extended part of the valve, means to hold the rubbing member upon the valve and positively hold one of the valve-portions seated, 100 said member adapted by pressure of an animal thereon to release the valve for the liberation of a single quantity of fluid.

11. The combination in a rubbing post, of a main fluid receptacle, a relatively smaller 105 receptacle including an opening connecting the receptacles, and a discharge opening in the outer wall of the said smaller one, a valve structure comprising two spaced portions each to close one of the openings, the 110 distance between the portions and the distance between the openings being unequal, a rubbing member beneath the receptacles mounted to swing on a vertical axis, and having an extension lying normally beneath 115 the discharge opening and arranged to engage and seat the valve on one of the openings, means elastically in control of the member to hold it in such engagement, and means constantly tending to operate the 120 valve in opposition to the movement imparted by the said member.

12. In a rubbing post, in combination a main fluid receptacle, a second smaller receptacle communicating with it including an 125 outlet for fluid, a valve interposed between the receptacles, elastic means constantly tending to hold the valve closed, a second valve to close the outlet and including a stem on which both valves are fixed, a rub- 130

bing member to directly engage the stem, elastic means controlling the member and through it holding the second named valve closed upon the outlet of the said second receptacle, the rubbing member adapted by pressure of an animal thereon to release the said second named valve and permit it to open to discharge the contents of the second receptacle and close the first named valve.

13. The combination in a rubbing post, of two receptacles, included in a single casting, one of them including an opening in each of two opposite walls, one of the latter opening outside the receptacles, the other permitting communication of one receptacle with the other, a single member within the inner receptacle having two valves thereon fixed relatively, each adapted to close one of the openings, said member extending outside the receptacle containing it, the valves adapted to close one opening and open the other, a spring constantly tending to seat one of the valves and hold the other open, and a rubbing member beneath the receptacles and in position to receive fluid therefrom including a spring engaging the member to normally hold one of the valves open and the other closed in opposition to the tendency of the first named spring, said rubbing member adapted by pressure of an animal thereon to release the valves for the liberation of a single quantity of fluid upon said member.

14. In a hog greaser, in combination, a submerged receptacle having an opening in two opposite walls, a separate valve for closing each opening fixed relatively to one another and adapted when moved to close one and open the other of the openings, a spring in control of the valves and constantly tending to seat one of them, a rubbing member operated by pressure of an animal and directly engaging the valve structure and adapted to seat one of the valves in opposition to the pressure of the spring, and means elastically in control of and constantly tending to hold the member in engagement with the said valve structure.

15. The combination in a hog oiler, of two receptacles one within the other included in a single one piece structure, the inner receptacle having an opening in one of its walls within the other receptacle and also having an outer discharge opening in one of its other walls, a valve structure comprising two portions, each adapted to close one of the openings but so spaced from one another that when one is seated the other remains unseated, said portions arranged to move perpendicularly to the plane of the parts having said openings, and a member adapted to bear elastically upon the valve structure for holding one of the portions normally seated and adapted when pressure is applied to it to release said valve struc-

ture, the latter adapted to seat as to its other portion when released.

16. The combination in a hog oiler, of two receptacles, one of them communicating with the other and including an opening in its wall for such communication, there being a discharge opening for one of said receptacles, a valve structure comprising two portions, each adapted to close one of the openings but so spaced from one another that when one is seated the other remains unseated, a member engaging the valve structure to hold one of the portions normally seated, adapted when pressure is applied to it to release said valve, and means constantly tending to seat the other valve portion when the valve structure is released.

17. In a hog oiler, the combination with a support and a receptacle for fluid, of an upright member arranged in position to be engaged by an animal and mounted on the support upon a vertical axis, the portion upon which the animal rubs being extended away from the axis of movement of said member, and means actuated by the member to release fluid from the receptacle directly upon it.

18. In a hog oiler, the combination with a support, a receptacle for fluid and mechanism to release fluid therefrom, of an upright member arranged in position to be engaged by an animal and mounted on the support upon a vertical axis, the portion upon which the animal rubs being extended away from said axis, said member arranged to operate said mechanism including a part to receive fluid directly upon it from said receptacle.

19. In a device of the character described, the combination of a support, a member pivoted relative to it upon a vertical axis adapted for a limited swinging movement, the same extending laterally from the line of its pivot, a part overhanging the member for discharging fluid upon it, and means associated with the part to release the fluid, said means being engaged and controlled by the said member.

20. In a device of the character described, the combination of a support, a member pivoted relative to it upon a vertical axis and adapted for a limited swinging movement, the same being extended laterally beyond the line of its pivot, and a part adapted for discharging fluid upon the member and including a valve engaged and operated by said member.

21. In a device of the character described, the combination of a support, a member pivoted relative to it upon a vertical axis and adapted for a limited swinging movement, the same being extended laterally beyond the line of its pivot, a part adapted for discharging fluid upon the member and including a valve, said member including a part

- having a cam surface normally engaging the valve, and means to hold the member elastically at one of its limits in engagement with said valve.
- 5 22. In a device of the character described, the combination with a support, a source of fluid supply and a rubbing member having an upright position pivoted relative to said support and including a part constituting 10 a pivoting portion, and a second part also constituting a pivoting portion adjustable upon said member, of a member engaged and moved by the said member to liberate fluid directly upon said member.
- 15 23. In a hog oiler, in combination, a receptacle, a second receptacle supplied with oil having an opening in each of two opposite walls, a valve structure including two parts one of them being normally seated

upon one of the openings and adapted to 20 move in a direction perpendicular to the planes in which the openings lie, and an elastically controlled member mounted to swing on a vertical axis and positioned below the receptacle independent of the valve 25 and of its movement and having a part adapted to directly engage and move the valve to unseat the described normally seated part and place the other upon its seat at its corresponding opening, said member adapted to be operated by pressure of an animal against it.

In testimony whereof I affix my signature, in presence of two witnesses.

ERNEST STARBUCK.
